US00D743617S

(12) **United States Design Patent**
Clifton-Draper et al.

(10) **Patent No.:** US D743,617 S
(45) **Date of Patent:** ** Nov. 17, 2015

(54) **LANTERN STOVE TOP**

(71) Applicants: **Julia D. Clifton-Draper**, New Port Richey, FL (US); **George E. Draper**, New Port Richey, FL (US); **Cristen Peterson**, Clearwater, FL (US)

(72) Inventors: **Julia D. Clifton-Draper**, New Port Richey, FL (US); **George E. Draper**, New Port Richey, FL (US); **Cristen Peterson**, Clearwater, FL (US)

(**) Term: **14 Years**

(21) Appl. No.: **29/483,801**

(22) Filed: **Mar. 3, 2014**

(51) LOC (10) Cl. **26-99**
(52) U.S. Cl. **D26/114**

(57) **CLAIM**

The ornamental design for a lantern stove top, as shown and described.

DESCRIPTION

FIG. 1 is a front elevation view of the lantern stove top showing our new design. The air vents are shown with broken lines and are provided for environmental purposes only and are not part of the claimed design;

FIG. 2 is a rear elevation view of the lantern stove top, showing the seam on the lantern stove top. The air vents and rivets are shown with broken lines and are provided for environmental purposes only and are not part of the claimed design; FIG. 3 is a right side elevation view of the lantern stove top. The air vents and rivets are shown with broken lines and are provided for environmental purposes only and are not part of the claimed design;

FIG. 4 is a left side elevation view of the lantern stove top. The air vents and rivets are shown with broken lines and are provided for environmental purposes only and are not part of the claimed design;

FIG. 5 is a top plan view of the lantern stove top, showing the prongs, or upper tabs. The small holes shown with broken lines in the upper tabs, as well as the lower tabs shown in broken lines are provided for environmental purposes only, and are not part of the claimed design;

FIG. 6 is a bottom plan view of the lantern stove top, showing the prongs, or upper tabs. The small holes are shown with broken lines in the upper tabs. These small holes shown with broken lines in the upper tabs as well as the lower tabs shown in broken lines are provided for environmental purposes only, and are not part of the claimed design; and,

FIG. 7 is a perspective view of the lantern stove top, showing the air holes, the upper tab holes and the rivets in broken lines, which are shown for environmental purposes only and are not part of the claimed design.
